FREEZING TRAY AND ICE STORAGE CONTAINER ARRANGEMENT FOR REFRIGERATORS

John A. Dahlgren and George W. Andriot, Louisville, Ky., assignors to General Electric Company, a corporation of New York

Filed Mar. 2, 1959, Ser. No. 796,590

4 Claims. (Cl. 62—344)

The present invention relates to household refrigerators and is more particularly concerned with a freezing tray and storage container arrangement slidably supported within a refrigerator storage compartment.

The present invention is an improvement over the invention of the copending application of Albert V. Melikian, Serial No. 796,589 filed concurrently herewith and assigned to the same assignee as the present invention, which invention was made by said Albert V. Melikian prior to the present invention. Therefore, it is not intended to claim herein anything shown or described in said Melikian application which is to be regarded as prior art with respect to the present invention.

In the usual household refrigerator, means are generally provided for supporting one or more freezing trays within the freezer compartment. A preferred position for the freezing trays from the standpoint of freedom from contamination is adjacent the top of the compartment above the remaining contents of the compartment. A shelf arrangement suitable for this purpose is described and shown in the aforementioned Melikian application as comprising a sliding shelf supporting both an ice storage receptacle and one or more freezing trays in such a manner that the receptacle and trays become accessible when the shelf is extended. The present invention is directed to, and has as an object the provision of, an improved structure so designed that the trays can be left in the compartment while the ice receptacle alone is slid forwardly.

Another object of the invention is to provide an improved ice supply means comprising an assembly including means for separately and slidably supporting a removable ice block receptacle and one or more freezing trays in such a manner that while access to the receptacle can be obtained without disturbing the freezing tray, when the entire assembly is in its extended position, the trays are so positioned that ice blocks can be harvested into the receptacle and the freezing tray refilled with water without removal from their supporting structure.

Further objects and advantages of the invention will become apparent as the following description proceeds and the features of novelty which characterize the invention will be pointed out with particularity in the claims annexed to and forming a part of this specification.

In carrying out the objects of the present invention, there is provided an assembly having means for slidably supporting an ice storage receptacle and at least one freezing tray for independent movement out of the compartment in such a manner that while the receptacle can be slid to an accessible position without disturbing the freezing tray, the ice blocks can also be harvested from the tray into the receptacle without removal of either from the assembly. For this purpose, there are provided a sliding shelf for supporting the ice receptacle and a sliding frame for supporting one or more trays in such a manner that the shelf can be moved to an extended position independently of the frame for access to the receptacle or both the shelf and frame can be ex-

2

tended to positions in which the tray can be pivoted about its support on the frame to a discharge position above the receptacle. In its preferred form, the invention forms part of a freezer compartment including a drawer assembly and the shelf carrying the receptacle is adapted to be supported and operated in part by the drawer.

For a better understanding of the invention reference may be had to the accompanying drawings in which:

10 Fig. 1 is a side elevational view, partly in section, of a refrigerator cabinet including the ice tray and storage receptacle arrangement of the present invention;

Fig. 2 is a fragmentary front view taken along line 2—2 of Fig. 1;

15 Fig. 3 is a fragmentary view similar to Fig. 1 but showing the receptacle in its accessible position;

Fig. 4 is a fragmentary view illustrating the operational features of one type of freezing tray suitable for use in the practice of the present invention; and

20 Fig. 5 is a view similar to Fig. 4 illustrating the position of the tray during the ice harvesting operation.

Referring to Fig. 1 of the drawing, there is shown a counter-height cabinet including an inner liner 1 forming a freezer compartment 2 for the storage of frozen foods. While this compartment is shown in an under-counter freezer, it is to be understood that it could also comprise the lower part of a combination refrigerator-freezer. In either case, as it is below what may be termed normal counter level, access to the contents thereof can be more readily obtained when the contents are stored in a drawer generally indicated by the numeral 3 rather than on shelves permanently positioned within the compartment 2. The compartment 2 is maintained at desired storage temperatures by means of an evaporator 4 that may be arranged as shown along the lower and rear walls of the compartment. The evaporator 4 forms part of a refrigerating system including a motor compressor unit 5 and a condenser (not shown).

25 The access opening to the storage compartment 2 is 30 closed by a closure member in the form of a drawer front 8 and the space between the drawer front 8 and the face of the cabinet is sealed by means of a gasket 6 extending around the peripheral edge of the drawer front 8.

35 The drawer front 8 is part of a drawer assembly that includes a pair of spaced slides connected together by front and rear cross members 10 to form an open cradle or framework for supporting a removable storage pan 11. The drawer front 8 is suitably secured to the forward end portions of the drawer slides 9 and the drawer structure 3 is slidably supported within the compartment 2 by drawer supports 13 secured to the opposite side walls 12.

40 For most efficient usage, it is of course desirable that the depth of a storage drawer or bin such as the bin 11 be kept within certain limits depending upon the material to be stored therein. In order to do this in a relatively high compartment such as that shown in the drawing, there is provided a second or upper storage bin 17 which is supported by the same framework as that supporting the lower pan 11 and which normally moves therewith when the drawer is opened or closed. For access to the lower pan 11 when the drawer is in its open position, this upper pan or bin 17 is so supported 45 that it can be moved separately back into the storage compartment 2 thus exposing the contents of the lower pan 11. To accomplish this result, the upper pan 17 is provided with a pair of rollers 18 which normally ride on the upper surface of the supports 13 and the forward end of the pan is supported on the slides 9 by means of a pair of legs 19. Means for anchoring or indexing the upper pan 17 relative to the slides 9 are provided in

50 55 60 65 70 75 80 85 90 95

the form of indentations (not shown) provided in the upper surface of the slide portion of the frame work and which are adapted to receive the feet or pads 21 provided on the legs 19.

When the drawer is moved to its open position, the feet 21 resting in the indentations cause the pan 17 to move forwardly with the remainder of the drawer assembly thus exposing the contents of the upper pan. If access is desired to the lower pan, it is necessary merely to lift or move the forward edge of the pan 17 to a position in which the feet clear the indentations whereby the upper pan can be slid rearwardly. The particular drawer structure thus far described is more fully described in Patent 2,843,441—Jewell, issued July 15, 1958, and assigned to the same assignee as the present invention and reference to that patent is made for a more complete description of the drawer and its mode of operation.

In accordance with the present invention, the stationary shelf provided in the freezer compartment shown in the Jewell patent for the storage of freezing trays is replaced with a sliding assembly which is an improvement over that of the aforementioned Melikian application and is so designed that the ice storage receptacle can be moved to an access position independently of the freezing trays.

With reference to Figs. 1 and 2 of the drawing, there is shown one embodiment of the present invention particularly adapted for use with the above-described drawer structure. The invention comprises a first shelf or framework 23 which extends substantially the full width of the compartment 2 and a second shelf or framework 24 which in the illustrated embodiment of the invention extends about half the width of the compartment 2. The shelf 23 is slidably supported at its rear corners by means of slides 25 which respectively ride on opposed guides 26 secured to the side walls of the compartment 2 above the drawer assembly while the forward edge of the shelf 23 is provided with a pair of legs 27 having pads 28 adapted to engage and ride on the side edges of the pan 17. By this arrangement the shelf 23 is slidably supported in both its open and closed positions by the guides 25 and the drawer assembly or more specifically the pan 17 forming part of that assembly. The left side of the shelf 23 as viewed in Fig. 2 of the drawing is in the form of an open frame designed to receive and position a removable ice storage receptacle 30 which extends about half the width of the shelf 23 and approximately the full depth thereof.

The second shelf or frame 24, which is in the form of a half shelf, overlies the right side of the shelf 23. One side of this frame 24 is in the form of a slide 31 which is disposed in a guide 32 provided along the mid section of the shelf 23 while the remaining three sides of the frame 24 are formed of heavy gauge wires 33 forming a cradle structure for receiving one or more freezing trays 34. The outer side or edge of the frame 24 is slidably supported at its forward end by a leg 35 slidably engaging the shelf 23 and at its rear end by means of an arm 36 having a roller 37 which rides on the adjacent guide 26 rearwardly of the slide 25 supporting the corresponding corner of the shelf 23.

To prevent forward movement of frame 24 when the shelf 23 is extended, there is provided a latch 38 shown in Fig. 3 of the drawing in the form of a spring finger at the rear end of the guide 26 for engaging the roller 37 when the frame is in its recessed position. This latch is of a strength such that while it will normally prevent frame 24 from moving forwardly when the shelf 23 carrying the receptacle 30 is moved to an access position, it can be released by a positive pull on the frame 24 so that the trays 34 can be moved to an accessible position outside the compartment 2 when it is desired to fill the trays with water or to harvest the ice blocks contained therein. In other words while the frame 24 is normally retained in the compartment 2 by means of the latch 38 so that the shelf 23 can be slid forwardly

without disturbing the frame 24, once the shelf 23 is in its extended position, the shelf 24 can be moved forwardly by the application of sufficient pressure to overcome the latching force of the latch 38. For the purpose of applying this opening pull, a handle 39 is provided on the frame 24.

Harvesting of the ice from the freezing trays into the ice receptacle 30 is accomplished with both the shelf 23 and the frame 24 in their extended positions. For this purpose the freezing trays employed in the practice of the present invention are of the type which include means for providing a relative movement between the ice blocks and the adjacent tray surfaces designed to break the bond between the ice and the adjacent surfaces and to discharge the ice blocks when the tray is moved from a normal or horizontal freezing position to an inverted position above the receptacle 30. One type of tray suitable for this purpose is illustrated more particularly in Figs. 4 and 5 of the drawing as comprising a rectangular pan 40 which is divided into a plurality of ice pockets by means of a movable wall grid that is preferably locked in the tray against detachment therefrom in such a manner that the grid and tray form a unitary structure. The grid structure includes a plurality of transverse dividers 42 and a longitudinal divider interlocked therewith and comprising a lower section 43 and an upper section 44. The longitudinal grid sections 43 and 44 are connected by means of a linkage generally indicated by the numeral 45 so that upon relative movement between a handle 46 and the tray, the two longitudinal divider sections are caused to move relative to one another causing tilting of the transverse dividers 42 and a release of ice blocks from the tray. As this type of tray structure is well known in the art, it is not believed necessary to describe further the detailed construction thereof. Furthermore, the present invention contemplates use of any freezing tray having means for releasing ice blocks contained therein when the tray is moved from an upright to an inverted position.

In order that the harvesting operation can be carried out without removing the tray from its supporting framework, the operating means such as the handle 46 is so designed that it normally rests in a slot 49 provided in the guide 31. With the handle thereby anchored in a fixed position, pivotal movement of the tray from its normal freezing position shown in Fig. 4 to its inverted position shown in Fig. 5 above the receptacle 30 causes the relative movement between the handle 46 and the tray required to tilt the transverse dividers 42 and release the blocks in the receptacle 30 when the tray reaches its inverted position as shown in Fig. 5. After harvesting of the ice, the tray is returned to its normal position and refilled with water. The frame 24 carrying the tray can then be pushed back into the compartment 2 to a position in which the latch 38 engages the roller 37 and the framework 24 can be left in this position until the next batch of ice blocks is ready for harvesting.

For the purpose of preventing the legs 27 of the shelf 23 from riding off the side edges of the pan 17, special track sections 50 may be provided on these edges. These track sections, which are secured to the side edges of the pan, each have upwardly extending flanges 51 which limit sideways movement of the shelf relative to the pan 17. Further by turning up the front and rear ends of these track sections 50, the same sections may be employed to limit and control the forward and rearward travel of the shelf 23. For example, the turned up portion 53 provided on the forward end of the track sections 50 will be engaged by the legs 27 to facilitate return of the shelf 23 to its normal or recessed position as the drawer is closed. A similar turned up section 54 provided at the rear ends of the track sections 50 can be employed to limit the rearward travel of the shelf 23 relative to the drawer assembly when the drawer is in an open position.

If it is desired that the ice receptacle 30 move to an accessible position each time the drawer is opened, indentations 55 may be provided at the forward ends of the track sections 50 which correspond to and have the same functions as the indentations provided in the lower pan 11. In other words with the legs 27 or more specifically the pads 28 in engagement with these indentations, the shelf 23 will be pulled forwardly along with the pan 17 whenever the drawer is opened. Access to the pan 17 is then obtained by disengaging the pads 28 from the indentations 55 and sliding the shelf 23 to its recessed position. On the other hand if it is desired that the receptacle 30 remain within the compartment 2 along with the freezing trays 34 except for when actual access thereto is desired, the indentations 55 can be omitted so that the shelf 23 will remain within the storage compartment 2 and the pads 28 will merely slide along the track sections 50 as the drawer is opened. In the event the frictional engagement of the shelf 23 with the guides 26 and with the frame 24 which is held in position within the compartment by the latch 38 is not sufficient to prevent forward movement of the shelf 23 during drawer opening, a spring latch similar to the latch 38 may be provided for engaging one or both of the slides 25 in their recessed positions.

From the foregoing description, it will be seen that there has been provided in accordance with the present invention an ice freezing and storage arrangement in which the freezing trays 34 are adapted to remain in the compartment 2 during normal operation of the drawer assembly. In this position the contents of the freezing trays cannot become contaminated by particles dropping from the foodstuffs or their wrappings during loading or unloading of the pans 11 and 17 and the possibility of spilling water therefrom during drawer opening is eliminated. With the drawer in an open position, the trays can be slid forwardly to an accessible position either for filling or harvesting purposes. Upon closure of the drawer both the shelf 23 and the frame 24 respectively carrying the ice receptacle 30 and the tray 34 are returned to their normal position within the freezer by contact of the forward end of the track sections 50 with the legs 27 provided on the shelf 23 and the frictional engagement of the frame 24 with the shelf 23. If the frictional engagement between the contacting portions of the shelf 23 and the frame 24 are not sufficient for this purpose, the slide 25 provided at the right rear edge of the shelf 23 will contact the roller 37 so that a positive closing action will be transmitted through the arm 36 to the frame 24.

While a specific embodiment of the present invention has been shown and described, it is not desired that the invention be limited to the particular construction shown and described and it is intended by the appended claims to cover all modifications within the true spirit and scope of the invention.

What we claim as new and desire to secure by Letters Patent of the United States is:

1. A refrigerator including a freezer compartment having an access opening at the front thereof, a shelf therein having substantially the same width as said compartment and slidably supported therein for movement between a normal position within said compartment and an extended position, a frame of a width less than said shelf, said frame being slidably supported on said shelf, an ice receptacle carried by said shelf, a freezing tray carried by said frame, said receptacle and tray being arranged so that they are in side-by-side relationship when said shelf and said frame are in their extended positions, means for supporting said freezing tray for pivotal movement thereof between a freezing position and a discharge position overlying said receptacle when said shelf and frame are in their extended positions, and releasable latching means for retaining said frame in said compartment when said shelf is moved to its extended position.

2. A refrigerator including a freezer compartment having an access opening at the front thereof, a drawer slidably arranged in said compartment, a shelf having substantially the same width as said compartment and slidably supported above said drawer for movement between a normal position within said compartment and an extended position, a frame of a width less than said shelf, said frame being slidably supported on said shelf, an ice receptacle carried by said shelf, a freezing tray carried by said frame and including a handle operable upon movement relative to said tray to discharge ice blocks from said tray, said receptacle and tray being arranged so that they are in side-by-side relationship when said shelf and said frames are in their extended positions, means for supporting the handle of said freezing tray on said frame for pivotal movement of said tray between a freezing position and a discharge position overlying said receptacle, releasable latching means for retaining said frame in said compartment when said shelf is moved to its extended position and means on said drawer for engaging said shelf and returning said shelf and frame from their extended to their released positions when said drawer is moved from its extended position to its recessed position.

25 3. A refrigerator including a freezer compartment, a sliding assembly for supporting an ice receptacle and a freezing tray within said cabinet, said assembly including a first shelf extending the width of said compartment and slidably supported on guides mounted on the side walls of said compartment, an ice receptacle, said shelf including means on one side thereof for removably supporting said receptacle, a frame normally overlying the other side of said shelf and having one side edge slidably supported on said shelf adjacent said receptacle, the opposite edge of said frame including an arm slidably supported on the guide on the adjacent side wall of said compartment and a leg at the front end thereof slidably engaging said shelf, a freezing tray including side edges normally resting on said frame, said freezing tray comprising an elongated tray and a grid structure secured thereto for movement relative thereto, said grid structure including a plurality of transverse dividers dividing said tray into a plurality of sections and arranged for tilting movement relative to said tray to loosen ice blocks 40 frozen in said sections, means for tilting said inclined dividers relative to said tray, said tilting means including an arm pivotally secured to said grid and extending downwardly along one end of said tray, said arm being anchored on said one side edge of said frame whereby tilting of said tray out of said frame to an inverted position over said receptacle causes said lever arm to actuate said dividers to discharge said ice blocks into said receptacle, and releasable latching means engaging said frame arm for retaining said frame and freezing tray 45 within said compartment when said shelf is slid forwardly from said compartment.

4. A refrigerator including a freezer compartment, a drawer in said compartment, a sliding assembly for supporting an ice receptacle and a freezing tray within said cabinet above said drawer, said assembly including a first shelf extending the width of said compartment and slidably supported on guides mounted on the side walls of said compartment and on said drawer, an ice receptacle, said shelf including means on one side thereof for removably supporting said receptacle, a frame normally overlying the other side of said shelf and having one side edge slidably supported on said shelf adjacent said receptacle, the opposite edge of said frame including an arm slidably supported on one of said guides and a leg at the front end thereof slidably engaging said shelf, a freezing tray including side edges normally resting on said frame, said freezing tray comprising an elongated tray and a grid structure secured thereto for limited movement relative thereto, said grid structure including 70 a plurality of transverse dividers dividing said tray into

a plurality of sections and arranged for tilting movement relative to said tray to loosen ice blocks frozen in said sections, means for tilting said inclined dividers relative to said tray, said tilting means including a lever arm pivotally secured to said grid and extending downwardly along one end of said tray, said lever arm being anchored on said one side edge of said frame whereby tilting of said tray out of said frame to an inverted position over said receptacle causes said lever arm to actuate said dividers to discharge said ice blocks into said receptacle, 10 and releasable latching means engaging said frame arm

for retaining said frame and freezing tray within said compartment when said drawer and shelf are slid forwardly from said compartment.
